UNITED STATES PATENT OFFICE.

HENRY C. SWAN, OF OSHKOSH, WISCONSIN.

DESIGN FOR A WHIFFLETREE-CLIP.

SPECIFICATION forming part of Design No. 22,670, dated August 1, 1893.

Application filed February 25, 1893. Serial No. 463,762. Term of patent 14 years.

To all whom it may concern:

Be it known that I, HENRY C. SWAN, of Oshkosh, in the county of Winnebago and State of Wisconsin, have invented a new and original Design for Whiffletree-Clips, of which the following is a full, clear, and exact description, reference being had to the accompanying drawing, which shows in perspective view a whiffletree-clip embodying my design.

The design consists of a whiffletree-clip of the shape substantially as herein described and shown in the drawing.

In the drawing, 2 represents the clip, whose body is made of general E-form, having a

vertical back portion 4, and three substantially parallel projecting branches 5, 6, 7, one at each end and one in the middle. At the back of the portion 4, and in the same plane therewith, is a loop-shaped protuberance 3.

I claim—

The design for whiffletree clips, substantially as herein shown and described.

In testimony whereof I have hereunto set my hand.

HENRY C. SWAN.
